ATTORNEY

UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

SWITCHING MECHANISM.

Application filed April 14, 1920. Serial No. 373,734.

To all whom it may concern:

Be it known that I, FRANK CONRAD, a citizen of the United States, and a resident of Pittsburgh, in the county of Allegheny and State of Pennsylvania, have invented 5 a new and useful Improvement in Switching Mechanisms, of which the following is a specification.

My invention relates to switching mechanisms and particularly to combined starting, ignition and lighting switches for service on automobiles.

One object of my invention is to provide 10 a switching mechanism of the above-indicated character that shall be simple and economical in construction and that shall be provided with means either for locking the various switches jointly or for locking only one of the switches in any of its 15 positions.

In operating an automobile, it is desirable 20 to jointly lock all switches in their "off" positions and also to lock the lighting switch in any of its positions when the ignition switch is in any position. Thus, when an automobile is parked, it is desirable 25 to have the starting switch and the ignition switch locked in their "off" positions and to lock the lighting switch either in the "off" or in an operative position, according to the time of day. Moreover, it is desirable 30 to lock the lighting switch in any of its operative positions when the ignition switch is in an operative position.

35 In a switch mechanism constructed in accordance with my invention, the ignition switch can be locked in its "off" position and the starting switch is mechanically interlocked with the ignition switch to prevent its operation when the ignition switch is in its "off" positions. The lighting switch may be locked either in its "off" position or in any of its operative positions when the ignition switch is in either the off or an operative position. If the lighting switch is locked when the ignition switch is in an operative position, the ignition will be automatically locked upon movement to the off position.

40 45 50 In the preferred embodiment of my invention, the ignition switch and the lighting switch severally comprise a rotatable contact cylinder having notches formed in it, in accordance with the positions of the

switch, and contact arms for engaging the 55 contact cylinder, not only to complete electric circuits, but, also, to accentuate the switch positions. The lighting switch is provided with a locking disk which is notched in accordance with the positions 60 of the lighting switch, and the ignition switch is provided with a locking disk which has one notch corresponding to the "off" position of the ignition switch. A locking mechanism is provided for operating 65 a latch member to control the locking of the various switches. The latch member is provided with a tooth for co-operating with the notches in the locking disk of the lighting switch, and an arm is provided on 70 the latch member for co-operating with the single notch in the locking disk of the ignition switch. A locking arm, which is controlled by a pin projecting from the ignition switch, is provided for locking the 75 starting switch when the ignition switch is in its "off" position.

In the accompanying drawing, Figure 1 is a plan view of a switching mechanism constructed in accordance with my invention; Fig. 2 is a plan view, with the casing removed, of the mechanism shown in Fig. 1; Fig. 3 is a plan view of the switching mechanism, with various parts removed; Fig. 4 is a bottom plan view of the 80 casing; Fig. 5 is a detail view of the starting switch; Fig. 6 is a detail view of the ignition switch, and Fig. 7 is a detail view of the lighting switch.

Referring to the drawing, a switching 90 mechanism 1 comprises a casing 2, of any suitable material, preferably aluminum bronze, and a base plate 3 of any suitable insulating material. The casing 2 is provided with lugs 4 having openings for attaching the switch mechanism, in any suitable manner, by screws or bolts to the dash board of an automobile. A plate 2^a is attached to the top of the casing 2 for indicating the various positions of the ignition 95 switch and the lighting switch.

The operative parts of the switch mechanism comprise a lighting switch 5 for controlling the lights of the automobile, an ignition switch 6 for controlling the ignition circuits, a starting switch 7, and a locking mechanism 8 for locking the starting switch, the ignition switch and the

lighting switch. The starting, lighting and ignition switches are mounted upon the base plate 3, whereas the locking mechanism 8 is mounted upon the casing 2.

5 The lighting switch 5 comprises a shaft 9 which has a bearing in the base plate 3 and projects through the top of the casing 2, as shown in Fig. 1. A lever 10 is mounted on a shaft 9 outside of the casing 2 and is attached to it in any suitable manner, as by means of a screw 11. Within the casing 2, a contact cylinder 12 and a locking disk 13 are mounted upon the shaft 9 and are adapted to be operated, in accordance 15 with the operation of the shaft, by the lever 10. The contact cylinder 12 is provided with notches 14 in its periphery which correspond to the operative positions of the locking switch.

20 The contact cylinder, which may be of any suitable insulating material, is provided with contact segments 15 which are embedded in it and are adapted to be engaged by the contact arms 16, 17, 18 and 19. The contact 25 arms 16 to 19 not only engage the contact segments for completing the various lighting circuits according to the position of the switch but also resiliently engage the various notches in the contact cylinder to accentuate 30 the switch positions. The contact arms 16 to 19, inclusive, are supported in any suitable manner upon the base plate 3 as by means of the contact terminals 20 to 23, inclusive.

35 The locking plate 13 is preferably made of insulating material and is provided with notches 24 which are formed in its periphery in accordance with the positions of the lighting switch. A pin 25 projects from the bottom 40 of the locking disk 13 and engages the sides of a recess 26 in the base plate 3 to limit the movement of the lighting switch.

The ignition switch 6 comprises a shaft 27 which has a bearing in the base plate 3 and projects through the top of the casing 2, as shown in Fig. 1 of the drawing. A lever 28 is mounted on that portion of the shaft 27 which projects through the casing 2 and is connected to it in any suitable manner, as by means of a screw 29. A contact cylinder 30 and a locking disk 31 are rigidly mounted upon the shaft 27 within the casing 2. The contact cylinder 30 is composed of any suitable insulating material and has 55 notches 32 formed in its periphery, in accordance with the positions of the switch. Contact segments 33, which are embedded in the cylinder 30, are engaged by contact arms 34, 35 and 36 for completing the ignition 60 circuits of the automobile.

The contact arms 34 to 36, inclusive, are resiliently mounted upon the base plate 3, not only for controlling the ignition circuit, but, also, for co-operation with the notches 65 32 in the cylinder 30 to accentuate the vari-

ous switches' positions. The locking plate 31 is provided with one notch 37 which corresponds to the "off" position of the ignition switch. A pin 38 projects from the bottom of the disk 31 and not only engages the sides of a recess 39 formed in the base plate 3 to limit the movement of the ignition switch, but, also, engages the sides of a notch 40 formed in a locking arm 41 to govern the locking of the starting switch. 75

The starting switch 7 comprises a stationary contact member 42 and a movable contact member 43 which is mounted upon a spring member 44. The movable contact member 43 is forced into engagement with the stationary contact member 42 by means of a rod 45 which projects through a hole 46 in the casing 2. The rod 45 is provided with an operating knob 46^a, an insulating tip 47, a collar 48 which engages the casing 2 for 85 limiting the movement of the rod and a groove 49 within which the locking lever 41 fits to lock the starting switch when the ignition switch is in its "off" position. A screw 50, which passes through a slot 51 in 90 the locking lever 41, is provided for maintaining such lever in position on the base plate 3.

The locking mechanism 8, which is shown in Figs. 1 and 4 of the drawing, comprises 95 a standard lock of any suitable type which operates a pin 52 for governing the movement of a latching plate 53, shown in Figs. 2 and 3 of the drawing. The latching plate 53 is disposed in a slot 54 of the base plate 100 3 and is held in position by means of a clamp 55 which is secured to the base plate by screws 56. A portion 57 of the latching plate 53 is constructed in the form of a tooth 59 to enter the notches in the locking 105 disk 13 and, also, as a support for a spring member 58.

A lever 60 is pivotally mounted upon the latching plate 53 and is biased into engagement with a stop member 61 by means of 110 the spring member 58. The lever 60 is provided with a tooth 62 which enters the notch 37 in the locking plate 31 when the ignition switch is in the "off" position and the latching plate 53 is moved to lock the various 115 switches. An up-standing portion 63 is provided on the latching plate 53 to be engaged by the pin 52 as it is given a movement of rotation by the lock. When the latching plate 53 is raised by the pin 52 engaging the 120 portion 63, the tooth 59 enters one of the notches 24 in the locking disk 13 to lock the lighting switch in whatever position it may be at that time.

If the ignition switch is in its "off" position when the latching plate 53 is raised, the tooth 62 enters the notch 37 and prevents further movement of the ignition switch. When the ignition switch is in its "off" position, it will be noted that the pin 38 upon 125

the locking disk 31 operates the locking lever to prevent any movement of the starting switch 7. If the ignition switch is in any other position, except its "off" position, when 5 the latching plate 53 is raised, the ignition and the starting switches are not locked but will be locked as soon as the ignition switch is returned to its "off" position.

Modifications in the mechanism and arrangement and location of parts may be made within the spirit and scope of my invention, and such modifications are intended to be covered by the appended claims.

I claim as my invention:

15 1. In a switching mechanism, the combination with an ignition switch, a starting switch, and a lighting switch having a plurality of operative positions, of means for locking the lighting switch in any of its 20 operative positions when the ignition switch is in an operative position, and for locking the starting and ignition switches in their off positions.

2. In a switching mechanism, the combination with an ignition switch having an operative and an inoperative position and a lighting switch having a plurality of operative positions, of means for locking the ignition switch in its off position and for locking the lighting switch in any position when the ignition switch is in either position.

3. In a switching mechanism, the combination with an ignition switch, a starting switch, and a lighting switch having a plurality of operative positions, of means for locking the lighting switch in any position when the ignition switch is in an operative position and for jointly locking the ignition and starting switches.

40 4. In a switching mechanism, the combination comprising a lighting switch and an ignition switch comprising a rotatable member having a plurality of positions and means for locking the lighting switch when the ignition switch is in an operative position, said means automatically locking the ignition switch upon its movement to the off position.

5. In a switching mechanism, the combination comprising a lighting switch, a starting switch, an ignition switch comprising a rotatable member having a plurality of positions, and means for locking the lighting switch in any position when the ignition switch is in an operative position, said means automatically locking the starting switch and the ignition switch when the ignition switch is returned to its off position and the lighting switch is in a locked condition.

6. In a switching mechanism, the combination with an ignition switch comprising a rotatable drum having a plurality of positions, a lighting switch, and a starting switch, of means for jointly locking all of

said switches and for locking the lighting switch independently of the starting switch and the ignition switch.

7. In a switching mechanism, the combination with an ignition switch comprising a rotatable member having a plurality of positions, and a lighting switch, of means for jointly locking said switches when the ignition switch is in its off position and for locking the lighting switch independently of the ignition switch when the latter switch is in operative position.

8. In a switch mechanism, the combination comprising a lighting switch and an ignition switch, each of said switches having a rotatable member, and means for jointly locking said switches when one of said switches occupies a certain position and for independently locking the other of said switches when said one switch occupies other than said certain position.

9. In a switch mechanism, the combination with a lighting switch having a contact cylinder, a plurality of switch members engaging the contact cylinder, and a disk connected to said cylinder and notched in accordance with the operative positions of the switch, and an ignition switch having a contact cylinder, a plurality of contact members engaging the contact cylinder, and a disk connected to said cylinder and having one notch corresponding to the off position of the ignition switch, of a lock mechanism, a latch member operated by said lock mechanism and having a tooth for co-operating with the notched disk of the lighting switch to lock said ignition switch in any position, and a pivotally-mounted lever having a tooth for co-operating with the notched disk of the ignition switch.

10. In a switch mechanism, the combination with a lighting switch having a contact cylinder and a notched disk connected to the cylinder, and an ignition switch having a contact cylinder, and a notched disk connected to the cylinder, of a lock mechanism, a latch member operated by said lock mechanism and having a tooth for co-operating with the notches in the disk of the lighting switch, a lever pivotally mounted on said latch member and a spring member for biasing the lever into engagement with the disk of the ignition switch when the latch member is in engagement with the disk of the lighting switch.

11. In a switch mechanism, the combination with a lighting switch having a contact cylinder notched in accordance with the operative positions of the switch, contact arms resiliently engaging said cylinder to complete lighting circuits and to accentuate the switch positions, and an ignition switch having a contact cylinder notched in accordance with the operative positions of the switch, and contact arms for engaging the

ignition cylinder to complete the ignition circuit and to accentuate the switch positions, of mechanism for locking the two switches in their off positions and for locking the lighting switch in any of its positions.

12. In a switch mechanism, the combination with a starting switch, and an ignition switch having a plurality of operative positions, said ignition switch having a con-

tact cylinder for completing the ignition circuit, of means comprising a latch member for locking the starting switch and a pin projecting from the cylinder of the ignition switch to operate said latch member.

In testimony whereof, I have hereunto subscribed my name this 1st day of April, 1920.

FRANK CONRAD.
